UNITED STATES PATENT OFFICE.

EL ROY L. PAYNE, OF LOS ANGELES, CALIFORNIA, ASSIGNOR TO PAYNE FURNACE AND SUPPLY COMPANY, OF LOS ANGELES, CALIFORNIA, A CORPORATION OF CALIFORNIA.

ELECTRICALLY-CONTROLLED VALVE FOR GAS BURNERS, ETC.

Application filed September 29, 1924. Serial No. 740,559.

This invention relates to means for operating valves for controlling the supply of fluids and especially valves for turning on and off the supply of fuel gas to furnaces, etc. The main object of the invention is to provide an electrically controlled means for remote control of the valve without necessitating the large electromagnets and relatively high current requirements ordinarily pertaining to such valves. In the electrically controlled valves now in use for control of fuel supply to gas heaters and the like the movement of the main valve itself is in general effected by electromagnetically operated means. Since the valve parts are relatively heavy, large electromagnets and the use of relatively high voltages are required. This is not only undesirable in itself but causes sparking at the contact points in the circuit with the result that such contact points become oxidized or burn away and must be replaced from time to time.

In accordance with my invention the movement of the main valve is effected by the pressure of the gas or other fluid which is being controlled, and electromagnetically controlled means are provided for controlling such pressure in such manner as to effect operation of the main valve. This not only permits smaller electromagnets, smaller electrical conductors, and lower voltages to be used, but practically eliminates the sparking and consequent deterioration of the contact points.

Another object of the invention is to provide means for continually maintaining a small supply of gas for a pilot burner located adjacent the main burner and for momentarily increasing the supply of gas to such pilot burner at the time the supply of gas to the main burner is turned on, in order to cause a flashing up or increase in size of the pilot flame so as to assist in and ensure lighting of the main burner. Furthermore, by means of such provision the pilot burner may be placed slightly below the zone of the main flame, thus preventing deposition of carbon on the pilot burner which ordinarily occurs when it is located within the zone of the flame from the main burner. This prevention of carbon deposition on or in the pilot burner is another object of the invention. Other objects and advantages of my invention will appear hereinafter.

The accompanying drawings illustrate 55 embodiments of my invention and referring thereto:

Fig. 1 is a section on line 1—1 in Fig. 2.

Fig. 2 is a section on line 2—2 in Fig. 1.

Fig. 3 is a plan view of the electromagnetic 60 control means and contact means therefor with the cover removed.

Fig. 4 is a partial section on line 4—4 in Fig. 2.

Fig. 5 is a wiring diagram of the electrical circuits.

Fig. 6 is a side elevation of a gas burner and pilot provided with the electrically controlled valve, the cover of the latter being partly broken away.

Fig. 7 is a partial vertical section on line 7—7 in Fig. 1.

Fig. 8 is a wiring diagram of the electrical circuits for a modified application of my invention.

The main valve comprises a casing preferably composed of two members 1 and 2, one of said members being provided with annular recess 3 and the other with an annular shoulder 4 cooperating with said recess. Said casing members 1 and 2 are so formed as to provide chambers 5 and 14 above and below the valve member and within the casing when said members are secured together for example by means of screws 6. The valve proper is adapted to be operated by fluid pressure and comprises suitable pressure-responsive means, for example, a flexible diaphragm 7 consisting of leather, fabric or other suitable material and a valve member 8 preferably of metal attached thereto, for example by means of bolt and nut indicated at 9 and 10. A valve seat 11 is provided with which said valve member cooperates so as to shut off communication between inlet 85 chamber 12 and chamber 14 below diaphragm 7. Said valve member 8 may be provided if desired with suitable washers or gaskets 13 of felt, leather, or other soft material adapted to form a tight joint. Said inlet chamber 12 is threaded as at 15 to receive the gas or other fuel supply pipe 16. A passage 17 leads from chamber 14 to outlet 90 communication 18 which is threaded as at 19 so as to receive the outlet pipe 20 leading 95 for example to the gas burner.

In order to operate the above described main valve I provide means for controlling

the admission of gas from the inlet pipe 16 to the chamber 5 on the upper side of the pressure-responsive means 7, said chamber 5 serving as a pressure chamber for operation of the valve. Such means may comprise for example a passage 22 formed in the casing members 1 and 2 and communicating at one end with inlet chamber 12 and at its other end with the valve port 23 in control valve 24 mounted in a cylindrical recess 98 in the upper part of casing member 1. When the parts are in the position shown in Figs 2 and 4 said valve port 23 is in communication through passage 25 and valve port 26 in said control valve with a passage 27 leading to pressure chamber 5. The gas from inlet chamber 12 is thus admitted to the upper side of diaphragm 7 as well as to the lower side of the valve member 8 and said valve member is thus kept in closed position due to the greater area subjected to pressure on the upper side and to the weight of the valve member itself.

Means are also provided for shutting off the supply of gas to the upper side of the diaphragm valve and at the same time establishing an outlet or discharge opening therefrom to permit escape of the gas from pressure chamber 5, resulting in the opening of valve member 8 due to the pressure existing only on the lower side thereof. For this purpose control valve 24 is adapted to be operated, for example by rotation on its vertical axis as hereinafter described, so as to move port 23 out of register with passage 22, and to bring port 21, which also communicates with passage 25, into register with an outlet passage 34 leading to the outer air and preferably as shown through the pilot burner. Suitable means, such as leaf spring 97, are provided for holding control valve 24 tightly against the bottom of the cylindrical recess 98, so as to prevent leakage of gas around said valve. As shown in Figs. 6 and 7 outlet pipe 34 is preferably formed partly in each of the casing members 1 and 2 and is provided at its outer end with a threaded portion 28 adapted to receive pipe 29 leading to the pilot burner 30, said pilot burner being of any suitable type and being preferably provided with a tip 31 of soap-stone or other material adapted to assist in maintaining a small flame of the desired shape and size. Outlet pipe 20 may lead from the valve means to a main burner 32 of any suitable type, a mixing device 33 being preferably provided for controlling the admission of air to the gas going to said burner. The pilot burner 30 is located adjacent and preferably slightly below the main burner 32.

I also provide for maintaining a small supply of gas to the pilot burner 30 at all times, for example by means of a bypass comprising small passages 35 and 36 communicat-

ing respectively with the passages 22 and 34 in the valve casing and connected with each other through valve opening 37 whose size may be carefully adjusted by means of needle valve 38 provided with thumb screw or other suitable means 39 for manual adjustment thereof. It is evident that with such a construction and arrangement of parts as above described, the upper casing member 1 may be removed, for example for inspection of the diaphragm valve, without disconnecting any of the gas inlet or outlet pipes, as these are all connected to the lower casing member 2.

Electrically controlled means are provided for effecting the operating movement of the control valve 24, such means comprising for example two opposing electro-magnets 40 and 41, mounted on a hollow supporting core 42, said core being in turn mounted on supports 43 on a top flange 51 of the casing member 1. Suitable operating means are provided for operation of the control valve upon energization of the electromagnets, such means comprising, for example, a plunger 44 slidably mounted within the hollow core 42 of the electromagnets and adapted to be moved in one direction or the other within said core upon energization of one or the other of said electromagnets. A projecting pin 45 may be connected to the plunger 44 and project through a slot 46 in the bottom of core 42 so as to engage a recess or slot 47 in the lever arm 48. Said lever arm may be mounted to rotate for example on a vertical stud or shaft 49 mounted on the top flange 51 of casing member 1, and may be adapted to operate control valve 24, for example, by means of an arm 52 rigidly connected to said control valve and provided at its outer end with an upturned portion 53 engaging in a groove or slot 54 in said lever arm 48.

Any suitable electrical control means may be provided for energizing one or the other of the electromagnets 40 and 41 in order to effect opening and closing movement of the valve as hereinafter described. For example in the form shown in Figs. 2, 3, 5, and 6, I may provide electrical circuit means for the said electromagnets, including thermostatic contact means and circuit-breaking contact means adapted to be operated upon the movement of the valve. As shown in said figures such means may comprise thermostat 57 mounted for example on support 58 and adapted to move in response to variations in temperature, said thermostat being located, for example, in a room which is to be heated directly or indirectly by the burner 32. Thermostat 57 may be provided at its outer end with a contact member 59 having two contact points 60 and 61 adapted to make contact respectively with contact points 62 and 63 on contact members 64 and

65. Said contact members 64 and 65 are preferably adjustable so as to make contact at different positions of the thermostat and may for example be adjustably mounted on 5 a supporting arc 66 pivoted for example, at 67, said contact members being adapted to be secured to said arc 66 in any position by means of set-screws 68. In order to provide for further adjustment the supporting 10 arc 66 may itself be adapted to swing to any position about its pivot 67 and to be held in any desired position by set-screw 69. From the contact member 59 a wire 70 leads to a suitable source of current for example to the secondary of a transformer whose primary is connected to an ordinary 15 lighting or other electrical circuit, or, as shown, to a battery 71, and from said source of current wires 72 and 73 lead to a spring 20 contact member 74. Said contact member 74 is made preferably of light flexible metal and at one end is tightly secured to the shaft or stud 49 of the lever arm 48, said shaft being adapted to turn with said lever arm, 25 said contact member engaging at its other end in a recess 76 in a fixed stud 77 mounted on the top flange 51, in such manner as to cause said contact member 74 to be bowed in one direction or the other, depending 30 upon the position of lever arm 48. Contact member 74 is provided with two contact points 78 and 79 adapted to make contact respectively with contact points 81 and 82 on the contact arms 83 and 84 mounted 35 on fixed studs 85 and 86 on an insulating support 87 mounted on the top flange 51. Suitable means, such as adjusting screws 111 mounted on studs 112, may be provided for adjusting the position of contact 40 arms 83 and 84. From the contact arm 83 wire 89 leads to one end of the winding of electromagnet 41 and from the other end of said winding wires 90 and 91 lead to the contact member 64 of the thermostatic 45 device. Similarly wires 93, 94 and 95 connect contact member 84, electromagnet 40 and the other contact member 65 of the thermostat. The arrangement is therefore such that the operating circuit of each electromagnet includes a pair of contact points 50 of the thermostat and also a pair of contact points adapted to break such circuit upon completion of the movement of lever arm 48, resulting from the energization of 55 said electromagnet. In order to protect the electromagnets and the contact members and other parts mounted on the top of the casing, a suitable removable cover 96 may be provided for such parts. 60 The operation of the above described form of my invention is as follows: Assuming that the parts are in the position shown in Figs. 2 and 3, the gas from inlet pipe 16 is admitted both above and 65 below the diaphragm valve, comprising dia-

phragm 7 and valve member 8, and said valve is therefore held in closed position as above described. The supply of gas to the main burner is thus cut off, while a small amount of gas is permitted to pass 70 through passages 22, 35, 36, and 34, and through pipe 29 to the pilot burner 30 to cause a small residual pilot flame to be maintained adjacent said main burner as indicated in dotted lines at 99 in Fig. 6. 75 Assuming further that the thermostatic device has been set to maintain a certain temperature, for example in a room heated by burner 32, such setting of the thermostat being effected by proper adjustment of supporting arc 66 and contact members 64 and 65, then if the temperature in said room should fall below the desired point, thermostat 57 will move so as to cause contact point 60 to make contact with contact point 62. 80 An electrical circuit will thus be established from the source of current 71 through wire 70, contact points 60 and 62, wires 91 and 90, electromagnet 41, wire 89, contact points 81 and 78, and wires 73 and 72, back to the 85 source of current. Electromagnet 41 is thereby energized and attracts the operating plunger 44, causing the same to move to the right in Fig. 2. In such movement of the plunger the projecting pin 45 thereon 90 engages lever arm 48 and causes it to swing to the position indicated in dotted lines at 48' in Fig. 3. This movement of lever arm 48 in turn operates control valve 24 through arm 52 and causes the same to move so as 95 to shut off communication between passages 22 and 27 and to open communication from said passage 27 to the pilot burner. The supply of gas to the upper side of diaphragm 7 is thus cut off and the pressure on said diaphragm is thereby relieved, permitting the valve controlled thereby to open and admit a full supply of gas through pipe 20 to the main burner 32. At the same time a portion 100 of the gas contained in chamber 5 is forced out by the upward movement of diaphragm 7 and is discharged through pipe 29 to the pilot 105 30 causing the pilot flame to momentarily flare up, for example, as indicated in dotted lines at 100 in Fig. 6. This momentary increase in the pilot flame constitutes one advantage of my invention as it ensures prompt lighting of the gas at the main burner, while permitting the pilot burner to be located below the main burner and 110 out of the zone of the flame produced by said burner, so as to eliminate deposition of carbon on or in the pilot burner. 115

The above described operation of lever arm 48 not only causes operation of the valve 120 but also causes contact member 74 to swing over to the position indicated in dotted lines at 74' in Fig. 3, so as to break connection between contact points 78 and 81 and make 125 connection between contact points 79 and 130

82, thus opening the circuit-breaking means in the circuit of the electromagnet causing such operation and closing the circuit-breaking means in the circuit of the other electromagnet. The electrical circuit is thus broken and a needless consumption of electricity with consequent overheating of the electromagnets, conductors, and contact points is prevented. This automatic breaking of a contact in the operating circuit upon operation of the valve is an important advantage of my invention when used in connection with thermostatic control. The bowing of contact spring 74 when in position corresponding to either open or closed position of the valve, causes it to positively complete its movement in either direction as soon as it is moved past dead center by one of the electromagnets, and also serves to hold the control valve firmly in either open or closed position.

Another advantage of my invention is that in case the pipe leading to the pilot burner should become clogged, thus causing the pilot flame to go out, as sometimes occurs, for example due to depositing of soot or dirt therein, reopening of the main valve is prevented. The reason for this is that upon operation of the control valve the escape of gas from chamber 5 above the diaphragm 7 is prevented due to the obstruction in its normal channel of escape to the pilot burner, and the main valve 8 is thus held closed.

The main burner will continue to burn until the room which is being heated has reached a temperature slightly in excess of the desired temperature, when the thermostat 57 will move in the reverse direction and cause contact to be established between contact points 61 and 63. In substantially the same manner as above described, electromagnet 40 will thereby be energized, which causes plunger 44 to be moved to the left in Fig. 2, such movement of the plunger causing the control valve and the contact members to be returned to their original position. Upon such return movement of the control valve communication from chamber 5 to the pilot burner is cut off and gas from inlet pipe 16 is again admitted to said chamber, causing the diaphragm valve to be returned to closed position and to shut off the supply of gas to the main burner.

Thermostat 57 may be located at any point which is to be maintained at a certain temperature or the burner may be used in conjunction with an automatic constant-temperature water heater in which case thermostat 57 or other suitable thermostatic device would be adapted to be heated by the water in said water heater so as to maintain the same at a constant temperature. The operation of the electrical control means and the opening and closing movements of

the valve would in that case take place in substantially the same manner as above described.

In some cases I may provide for push button or other manual control of the electrical control means instead of thermostatic control thereof. For example as shown in Fig. 8 a pair of push buttons 103 and 104 may be located at any convenient point and adapted to make contact with a contact member 105. Said push buttons may be connected respectively by wires 106 and 107 to electromagnets 40 and 41, said electromagnets being connected by wire 108 to a source of current 71 from which a return wire 109 leads to contact member 105. Operation of push button 104 will then cause energization of electromagnet 41 which will in turn cause opening of the main valve 7 together with the momentary flaring up of the pilot flame as above described. Operation of push button 103 on the other hand will close the main valve and cut off the supply of gas to the main burner 32.

While I have described and shown my invention only as applied to control of the gas supply for a burner, and while some of the above described advantages thereof may be realized only in such connection, it is evident that an electrically controlled valve of similar construction and operation may be used to turn on and off the supply of any fluid, for example liquid fuel, compressed air, water, etc. In cases where the fluid under control is not used for combustion, no pilot flame is necessary and the means for continually maintaining a small residual supply of the fluid may therefore be eliminated. The essential feature of my invention, however, namely the operation of the main valve by the pressure of the fluid itself, and the control of such fluid pressure by electrically controlled operation of a control valve, is applicable in any such case, and the above-described advantages thereof as regards smaller electromagnets, lighter electrical conductors, lower voltages, longer life of the contact points, etc., may always be realized by such a combination.

What I claim is:

1. In combination with a gas burner provided with a pilot burner, a valve for controlling admission of gas to said gas burner and said pilot burner comprising a valve casing provided with inlet passage means and with outlet passage means connected to said burner, diaphragm valve means controlling communication between said inlet and outlet passages and adapted to be opened by the pressure in said inlet passage, a pressure chamber at the opposite side of said diaphragm valve from said inlet passage, means for conducting gas from said inlet passage to said pressure chamber, means for conducting gas from said pressure

- chamber to said pilot burner, open passage means establishing communication at all times between said inlet passage and said pilot burner for maintaining a small flame
- 5 at said pilot burner, and auxiliary valve means controlling communication between said inlet passage and said pressure chamber and between said pressure chamber and said pilot burner in such manner that communication between the pressure chamber and the pilot burner is established simultaneously with shutting off the communication between the inlet passage and the pressure chamber, thereby effecting release of pressure
- 10 sure in said pressure chamber and permitting the opening movement of said diaphragm valve by the pressure in said inlet passage to displace gas from said pressure chamber through said pilot burner and thus cause a momentary increase in the flame at said pilot burner.
2. In combination with a gas burner provided with a pilot burner, a valve for controlling supply of gas thereto comprising a valve casing provided with inlet and outlet passages, a diaphragm valve within said valve casing and exposed at one side to said inlet passage, a valve seat with which said diaphragm valve cooperates to control communication between said inlet and outlet passages, a pressure chamber at the other side of said diaphragm valve, said diaphragm valve being adapted to be held closed against said valve seat by pressure in said pressure chamber but to be opened by pressure in said inlet passage upon release of pressure from said pressure chamber, means for conducting gas from said outlet passage to said gas burner, by-pass means for continually conducting a small amount of gas from said inlet passage to said pilot burner, means for conducting gas from said inlet passage to said pressure chamber, means for conducting gas from said pressure chamber to said pilot burner, and control valve means adapted to simultaneously cut off communication between said inlet passage and said pressure chamber and establish communication between said pressure chamber and the pilot burner.
3. In combination with a gas burner provided with a pilot burner, an electrically controlled valve comprising a casing provided with inlet and outlet passages and with a valve seat and a valve cooperating therewith to control communication between
- said inlet and outlet passages, means for supplying gas to said inlet passage, means for conducting gas from said outlet passage to said gas burner, a diaphragm connected to said valve for control thereof, a pressure chamber on one side of said diaphragm, said diaphragm being adapted to operate so as to close said valve upon admission of gas to said pressure chamber and being subject at its other side to the pressure in said inlet passage, whereby said valve is adapted to be opened upon the release of gas from said pressure chamber, a control valve, means for conducting gas from said inlet passage to said control valve, means for conducting gas from said control valve to the pilot burner, said control valve being adapted to control communication between said inlet passage and said pressure chamber, and between said pressure chamber and said pilot burner, and electrically controlled means for operating said control valve.
4. An apparatus as set forth in claim 3, and comprising in addition by-pass means communicating with said inlet passage and with the pilot burner and adapted to conduct a small amount of gas for maintaining a residual flame at said pilot burner independently of the operation of the valve.
5. In combination with a gas burner, a valve for controlling admission of gas thereto provided with an inlet passage and an outlet passage, diaphragm valve means controlling communication between said inlet and outlet passages and adapted to be opened by the pressure in said inlet passage, a pressure chamber in such position that creation of pressure therein acts upon said diaphragm valve to close the same against the pressure in the inlet passage, gas-supply means for supplying gas under pressure to said pressure chamber, gas-exit passage means for conducting gas from said pressure chamber to a point adjacent the gas burner, and auxiliary valve means adapted upon operation in one direction to simultaneously open the gas supply passage means and close the gas exit passage means, and upon motion in the other direction to simultaneously close the gas supply passage means and open the gas-exit passage means.
- In testimony whereof I have hereunto subscribed my name this 17th day of September, 1924.

EL ROY L. PAYNE.
